COMBINED TELEPHONE RINGING AND INDUCTION COIL ARRANGEMENT

Dante Tini, Milan, Italy, assignor to International Standard Electric Corporation, New York, N. Y., a corporation of Delaware

Application December 19, 1955, Serial No. 561,706

Claims priority, application Italy December 24, 1954

13 Claims. (Cl. 179—81)

This invention relates to telephone equipment and more particularly to improvements in subscriber sets incorporating induction and ringing coils and utilizing polarized electromagnetic ringers.

Telephone designers have striven in the past to reduce the size of the components contained in telephone subset bases thereby achieving a reduction in weight and cost of the equipment. Three important elements contained in the base of a telephone subset are the ringer, the induction coil and the capacitor. Important advances have recently been made in the manufacture of capacitors and equally important advances have been made in the development of high quality magnetic materials suitable for the use as cores of induction coils and magnetic circuits of the ringers resulting in considerable reduction in the physical size of those components and yet maintaining efficient performance. Despite the advances, it has been necessary to separately mount the ringer and induction coils in the subsets and applicant has now devised a new type of telephone subset of a smaller size which is achieved by the consolidation of the magnetic core for the ringer with the magnetic core of the induction coil each using a common magnetic path.

Accordingly it is an object of the present invention to provide a new type of polarized ringer of simple construction, of small size and having incorporated as a part of the magnetic core of the ringer, the magnetic core of the induction coil.

A feature of this invention is the use of a magnetic circuit of simple form which permits the use of a permanent magnet of the bar type and of small size, but disposed in such a way as to obtain high magnetic efficiency and sensitivity in the ringer operation.

Another feature of the invention is the employment of a magnetic core having a branch which forms one of the sides of the induction coil core and having two other branches carrying the coils for the ringer.

A further feature of the invention for improving the mounting of some members of the ringer and lowering its costs of manufacture, consists in a device for clamping the permanent magnet to the laminated core which firmly holds the magnet to the core in its right position and bears the shaft of the swinging armature of the ringer motor, firmly holds the two spools carrying the electrical windings and which are placed on the two side arms of the magnetic core of the ringer without using supplementary clamping parts.

The above-mentioned and other features and objects of this invention and the manner of attaining them will become more apparent and the invention itself will be best understood, by reference to the following description of an embodiment of the invention taken in conjunction with the accompanying drawings, wherein:

Fig. 1 is a front diagrammatic view of the ringer including the features of the invention;

Fig. 2 is a view in elevation of the laminated core

2

structure of the magnetic assembly including a permanent magnet;

Fig. 3 is a side diagrammatic view of a portion of Fig. 1 showing the mounting of the swinging armature of the ringer and its connected hammer;

Fig. 4 is a detail of the folded plates for clamping the permanent magnet shown in Fig. 2 to the core;

Fig. 5 illustrates the mounting of the armature and the attached hammer;

Fig. 6 is a view of the armature pivot pin shown in Figs. 1 and 3; and

Fig. 7 is a front view of a retaining plate which retains the armature pivot pin shown in Figs. 1, 3 and 6.

Referring now to Fig. 1, there are shown some of the principal components of a telephone subset box and which comprise a pair of bells 11, 11', a hammer 8 carried by rod 24 and coupled to armature 5. The armature is actuated by means of ringing coils 6, 7 in response to the alternating signalling current applied to coils 6, 7, as is well known by those skilled in telephony. There is also shown an induction coil 25 which acts as a transformer to couple the telephone receiver (not shown) to the line (not shown). The coils 6, 7 and coil 25 are mounted on a unitary core structure 1 which consists of laminations of a paramagnetic material having substantially a W-shaped structure as is more clearly seen in Fig. 2, consisting of a pair of vertical outer arms 2, 3 and a short central vertical arm 4; the coils 6 and 7 adapted to encircle arms 2 and 3, respectively. The central arm 4 has a small bar-shaped permanent magnet 14 extending in prolongation thereof. The lower portion of the core 1 consists of two oppositely disposed L-shaped portions 12 and 13, separated by air gaps 15 and 15'. The winding of induction coil 25 is adapted to encircle the long arms of core portion 13. It will be seen that the axes of coils 6 and 7 are at right angles to the axis of coil 25 so that there is a minimum of inductive coupling thereamong.

Returning to Fig. 1, the magnetic core 1 is fastened to two suitable brackets 9 and 10 by means of fastening devices 33, 34 which extend through outer fastening plates 35, 35' into brackets 9 and 10, respectively. The core 1 is thus sandwiched between the brackets 9, 10 and plates 35, 35'. The bells 11, 11' may be mounted in the box of the subset in any desired way or may be mounted by means of suitable brackets (not shown) from core 1.

The magnet 14 has a cross-section similar to that of central arm 4 and is provided with a U-shaped slot 36 cut into its upper surface.

In order to mount the magnet 14 atop the central arm 4, I provide a pair of opposed brackets 16 and 17 made of a suitable material which brackets are shown more particularly in Fig. 4. The brackets 16 and 17 comprise a rectangular straight portion 16a and 17a, respectively, and an upper 3-sided portion 16b and 17b, respectively. The upper portions referred to are adapted to form the outline of a rectangle when placed in opposition to each other, the rectangle having an inside dimension corresponding to the perimeter of the magnet 14. Brackets 16 and 17 are each provided with a pair of holes 28 and 29 in the straight portions 16a and 17a, respectively, the sets of holes adapted to be in register when the brackets are opposed as shown in Fig. 4. The said brackets are adapted to be mounted on the central arm 4 through which a pair of holes may be drilled and suitable fastening devices such as 18 (Fig. 3) may extend thereby to firmly grip the brackets 16 and 17. The holes 28 and 29 in bracket 17 may be threaded to receive the fastenings 18, if desired. The brackets 16 and 17 in their upper portions 16b and 17b, respectively are each provided with

an aperture 30, 31 as shown in Fig. 4 and through which a pivot pin 21 is adapted to be inserted as shown clearly in Fig. 3. Brackets 16 and 17 are also provided with a pair of opposed outwardly extending lugs 26 and 27, the function of which will be later explained. The magnet 14 is provided with a transverse U-shaped slot 36 as shown in Fig. 2. The slot 36 is adapted to be aligned with the apertures 30 and 31 in brackets 16 and 17 and is adapted to accommodate the pivot pin 21 as shown in Fig. 3. Ringing coils 6 and 7 are adapted to be placed over outer arms 2 and 3, respectively as shown in Fig. 1. The lug portions 26 and 27 are adapted to extend over the cheeks 2a and 3a of said windings, respectively, as shown clearly in Fig. 1 to prevent the windings from being moved upwardly.

Cooperating with the coils 6 and 7 there is provided a balanced armature 5 and which comprises a straight portion 37 extending over the tops of the core arms 2 and 3 and having two downwardly extending studs 38, 38' made of diamagnetic material and which studs are adapted to cooperate with the upper surfaces of the arms 2 and 3 and prevent magnetic adherence thereto. The configuration of armature 5 is clearly shown in Fig. 5. The central portion of armature 5 is bent over downwardly on opposite sides thereof to form a U-shaped structure clearly shown in Fig. 3 and one of the arms of the U is extended perpendicularly outward at 22a to receive one end of rod 24 which extends perpendicularly therefrom and at the opposite end of which hammer 8 is attached. The U-shaped arms 22 of the armature 5 are provided with a pair of apertures 32 which are in register.

The induction coil 25 is mounted on the long leg of the L-shaped member 13 as shown clearly in Fig. 1 and it will be seen that the flux path of the induction coil includes the long arm 12 of the core 1 and that portions of the same arm 12 are included in the flux path of the coils 6 and 7, said portions being respectively between arms 2 and 4 and arms 3 and 4. Air gaps 15 and 15' prevent saturation of the magnetic material of the core 1. The assembly of the structure shown in Fig. 1 is relatively simple and includes the placement of the winding 25 on the leg 13, the clamping of the core 1 to the brackets 9 and 10; the placement of coils 6 and 7 over the arms 2 and 3; the placement of the magnet 14 upon the arm 4 as shown in Fig. 2; the clamping of the magnet by means of the brackets 16 and 17; the placement of armature 5 in the position shown in Fig. 3; the placement of pivot pin 21 through the apertures 30, 32, 31 and 32', respectively. The lugs 27 and 26 extend over the cheeks 2a and 3a of coils 6 and 7, respectively, and retain them in position on the arms 2 and 3.

The configuration of pivot pin 21 is more clearly shown in Fig. 6 where it will be seen that the pin 21 includes a circumferential slot cut near one end of the pin and marked 21a. Pin 21 is inserted so that the slotted portion 21a extends outwardly from the left portion of the structure as shown in Fig. 3 so that the retaining plate 20 may retain it in position. The configuration of retaining plate 20 is clearly shown in Fig. 7. The retaining plate 20 consists of an off-set shaped piece of metal having portions 20a and 20b extending in parallel planes and joined by angular portion 20c. The upper portion 20a is provided with a key-hole slot 20d and the lower portion 20b is provided with a semi-circular slot 20e. The key hole slot 20d is provided to permit the insertion of member 20 over the left hand extending portion of pivot pin 21 until the plate 20 is in alignment with the slot 21a. The plate 20 is then drawn downwardly and the narrow portions of the slot 20d are adapted to prevent lateral movement of the pivot pin while permitting rotary movement thereof. The semi-circular aperture 20e is adapted to fit over bracket 16 and underneath fastening device 18. It will thus be seen that assembly of the device is simple and therefore economical. The structure of Fig. 1 may then be mounted to the

5

base of a box (not shown) by means of the brackets 9 and 10 which support the entire ringing and inductive structure.

There is no problem of inductive losses since the induction coil 25 is not in operation when the windings 6 and 7 are energized and vice versa. The common flux path in the portion 12 as described above renders a saving in space and material as will be obvious to one skilled in the art.

While I have described above the principles of my invention in connection with specific apparatus, it is to be clearly understood that this description is made only by way of example and not as a limitation to the scope of my invention as set forth in the objects thereof and in the accompanying claims.

15

What is claimed is:

1. A telephone sub-set comprising signal receiving means and inductive coupling means for coupling said sub-set to a line, said signal receiving means comprising first ferromagnetic core means, said inductive coupling means comprising additional ferromagnetic core means, means interconnecting both said core means at a given angle to provide a common flux path for both said signal receiving means and said inductive coupling means while maintaining maximum inductive de-coupling therebetween.

2. A telephone subset as claimed in claim 1, wherein said interconnecting means comprises a magnetic core comprising a pair of spaced parallel outer arms, a central arm intermediate said outer arms, each of said arms mounted on a base portion extending normal to said arms, a fourth arm extending parallel to said base portion and a pair of interconnecting portions spacing said base portion from said fourth arm.

3. A telephone sub-set as claimed in claim 2 further comprising a permanent magnet attached to the end of said central arm in a manner whereby the total length of said central arm and said magnet is equal to the length of either of said outer arms.

4. A telephone subset as claimed in claim 2, wherein said signal receiving means comprises a pair of signalling coils, each coil extending over a different one of said outer arms, and said inductive coupling means comprises an induction coil extending over said fourth arm, whereby said outer arms and said fourth arm constitute magnetic cores for said signalling coils and said induction coil, respectively.

5. A telephone subset as claimed in claim 4, wherein said central arm further comprises a pair of brackets for mounting said magnet to said arm, each of said brackets having apertures for accommodating fastening devices for fastening to said arm, and a further aperture for accommodating a pivoting element.

6. A telephone subset as claimed in claim 5, wherein said permanent magnet is provided with a U-shaped slot in register with the further apertures in said brackets.

7. A telephone subset as claimed in claim 1, wherein said signal receiving means comprises a centrally balanced armature and a hammer extending in a direction normal to the length of said armature.

8. A telephone subset as claimed in claim 7, wherein said armature includes a U-shaped central portion having an aperture through each of its arms, said apertures in register.

9. A telephone subset as claimed in claim 8, further comprising a pivot element adapted to pass through the apertures in the central portion of said armature, the further apertures of said brackets and the U-shaped slot in said magnet.

10. A telephone subset as claimed in claim 9, wherein said pivot element comprises a circumferential slot adjacent an end thereof.

11. A telephone subset as claimed in claim 10, further comprising a retaining element for retaining said pivot element in a fixed axial position, said retaining element

comprising an off-set plate having a key hole slot therein, the narrow portion of said slot adapted to slidably fit within the circumferential slot in said pivot element, said plate having a lower portion adapted to be clamped to one of said brackets and said central arm.

12. A telephone subset as claimed in claim 5, wherein each of said brackets is provided with an opposite outwardly extending lug, said lugs adapted to extend over said signalling coils to retain said coils in position on said outer arms.

13. A telephone subset as claimed in claim 12, further comprising a pair of core mounting brackets for mounting all of said arms as a unitary structure.
